& Chemical Corporation, a corporation of Del-
aware

Application December 18, 1931, Serial No. 581,862

6 Claims. (Cl. 103—178)

The present invention relates to a device for pumping liquids and is particularly applicable to the dispensing of liquid fumigants, such as liquid hydrocyanic acid, in measured doses.

5 In the fumigation of enclosed spaces by means of liquid hydrocyanic acid, it is desirable to provide dispensing means for such fumigants of a character which will enable the operator to accurately gauge the dosage to be pumped or ejected, 10 and the invention is particularly directed to a pump of the above type.

In the use of liquid hydrocyanic acid as a fumigant, the pumping or dispensing devices of the piston type usually contain a hose or other tubular element attached to the pumping device whereby the liquid hydrocyanic acid may either be sprayed from the end of the tube or hose into the space to be fumigated or through any approved system of heat transfer be gasified before ejection from the end of the tube or hose. In devices of the type described above, there has heretofore been some difficulty in the field due to the fact that air or gas pockets form beneath the piston, and/or at the end of the down stroke of the piston 25 used to force the fumigant into the tube and out of the nozzle, a certain amount of the liquid remained in the pump barrel. Where the fumigant discharge aperture is at or near the bottom of the pump, as is usual, the air bubbles or formed gas bubbles hang in the space beneath the piston and are only expelled if a sufficiently high velocity of the outgoing liquid obtains. Gas or air pockets are put under compression by the piston and cause 30 a discharge or dribble after the completion of the pump stroke, due to expansion. This necessarily causes inaccurate dosage. Due to the fact that the outlet for this liquid, that is, the connection between the pump barrel and the dispensing hose, was substantially at the bottom of the 35 former and in close proximity to the head of the piston at the end of its stroke, dribbling frequently occurred. This is a very dangerous circumstance, particularly when using liquid hydrocyanic acid as a fumigant, for the reason that this material is 40 highly toxic to life even in small quantities.

One of the principal objects of the invention, therefore, is to devise a pump system which will prevent this dribbling or undue leakage of liquid fumigant after the end of the pump stroke has 45 been reached whether due to trapped and expanding gas or gravitational flow.

In carrying out the invention, I may accomplish the above result by placing the connection between the dispensing tube and the pump barrel 50 at or near the top of the latter so that any gas

or air bubbles will immediately rise and pass out through the discharge opening, and the tendency for any liquid remaining in the pump barrel to escape through the tubes is considerably lessened.

Other important features of the invention reside in the provision of a substantially cylindrical piston operable within a pump barrel or casing upon which is superimposed a dome within which the piston may rise. The top of the piston is arranged to be open and the bottom thereof is provided with a valve mounted on the end of the piston rod, the rod being so arranged that during the first portion of its up stroke, the valve is unseated and during the remainder of its up stroke, the entire piston is carried upwardly into 15 the dome. An inlet for the liquid fumigant is provided in the pump, and due to the fact that the top of the piston is open, the fumigant under the action of gravity flows into the inside of the piston, and when the valve in the bottom of the 20 piston has been unseated on the first portion of the up stroke of the piston rod, the liquid fumigant flows through the valve to a point beneath the head of the piston as the latter is raised to the desired extent, depending upon the dosage 25 desired. A flexible washer having a depending skirt of material extent surrounds the cylindrical piston to prevent the passage of liquid fumigant from the pump barrel past the walls of the piston and into the dome. In order to insure the prevention 30 of this escape and consequent inaccuracy of dosage, a coil spring is located in the head of the pump barrel or casing and surrounds the depending skirt of the washer. The spring is so arranged that it forcibly bears against the skirt and thus 35 insures close contact between the washer and the piston. While the spring is not essential, it is highly desirable as a precautionary measure. This feature insures sufficient friction between the washer and the piston to prevent dropping of the 40 latter under action of its own weight ahead of the dosage stroke, with consequent dribbling and inaccurate dosage.

The invention further consists in the novel 45 arrangement, combination and construction of parts more fully hereinafter shown and described.

In the drawings—

Fig. 1 is a side elevation of a device embodying my invention,

Fig. 2 is a front elevation of the device of Fig. 1,

Fig. 3 is a sectional elevation through the pump assembly,

Fig. 5 is a fragmentary elevation of the dosage adjustment mechanism.

Fig. 6 is a sectional view along the line 6—6 of Fig. 5, and

5 Fig. 7 is a perspective view of the stepped schedule.

Referring now with particularity to the embodiment illustrated, I have shown a base at 1 upon which is mounted a pump barrel or casing comprising a bottom casting 2, the barrel or casing proper 3, and an upper casting 4. The parts 2, 3 and 4 will be referred to generally hereafter as the pump barrel 3.

Suitably mounted upon the upper casting 4 is 15 a dome 5 provided with a valved fluid inlet 6 carrying a strainer housing 6a.

As shown in Fig. 3, a piston is located within the pump barrel 3 consisting of a cylindrical portion 7 spaced from the walls thereof. The top of 20 the piston 7 is open to permit a liquid entering 20 the dome at 8 to flow therewith.

Suitably mounted in the top 9 of the piston 7 is a bushing 10 through which a piston rod 11 passes. At the bottom of the piston rod is located a valve 12 adapted to seat in the center of the piston head 13. Surrounding the lower portion of the piston rod 11 is a spacer tube 14, the top of which terminates short of the bottom of the bushing 10. This is for the purpose of permitting the valve 12 to unseat during the first portion of the upward movement of the piston rod 11 or until the top of the tube 14 contacts with the bottom of the bushing 10. The upper portion of the dome is provided with a cavity through 35 which the piston rod 11 passes, and the cavity is provided with the usual packing 15, follower 16 and packing nut 17.

In order to insure the prevention of escape of liquid from beneath and around the piston to a 40 point within the dome, which would consequently cause irregularity and inaccuracy in dosage, a flexible washer 18 is provided secured between the upper casting 4 of the pump barrel and a ring member 19. The washer is provided with a depending skirt 20 making substantial surface contact with the piston 7, and a coil spring 21 is provided located within a recess in the upper casting 4 and forcing the depending skirt 20 of the washer 18 into close and intimate contact with the outer 45 walls of the piston 7. In order to prevent the hardening of and consequent lowering of the efficiency of the washer 18, means are provided to lubricate the same. This may conveniently consist of an oil cup 22 provided with the usual 50 valve 23, the cup 22 communicating with a conduit 24, the oil passing therefrom into the oil groove 25 in the ring 19 to the washer. The mere adjustment of the valve 23 will cause suitable 55 distribution of the oil over the entire surface of the washer 18.

The lower casting 2 is provided with a sediment trap 26 and drain valve 27 through which any scale or other accumulation may be removed as desired.

65 Set into the upper casting 4, which is at or near the top of the pump barrel, is a liquid outlet 28 containing a check valve which communicates by means of the bore 29 with the space between the piston 7 and the pump barrel 3.

70 In order to operate the piston rod and piston, a pump lever 30 is provided, being pivoted to the top of the piston rod as at 31 and fulcrumed on top of the link 32 pivotally carried as at 33 on the support 34. The support 34 is provided with 75 two legs, one of which is secured to the top of

the dome 5 and the other to the bottom flange of the dome. The opposite end of the pump lever terminates in a handle member adapted to be grasped by the operator.

The dosage may be fixed and determined by means of an adjustment mechanism. Operation of the dosage control and its means of adjustment is as follows:

A stepped schedule device comprising steps 40 and 40a are adjustably secured to the top of lever 10 30 as by means of screws or the like. The height of the steps on member 40 is about five times the height of those on member 40a. Pressing the lever 30 to the right side of the frame 37 and raising until the step on member 40a is stopped by adjustment screw 41, lifts the piston to such a height that the down stroke will eject a one unit dosage.

Pressing the lever 30 to the left side of frame 37, and raising until the step on member 40 is 20 stopped by adjustment 39, lifts the piston to such a height that the down stroke will eject five units.

Obviously any other desired relationship between the members 40 and 40a and stops 39 and 41 may be used to eject other multiples of units. 25

It will be noted that there is sufficient side play between the lever 30 and the rigid frame parts 36 and 37 to permit the lever to be raised past the one unit stop 41 when a greater amount is to be ejected.

30 The lever 30 may conveniently carry designations indicating the dosage when the members 40 and 40a are in any particular position, as shown in Fig. 5. For example, as shown with the setting of this figure, when the lever is pressed to the right to use the one unit schedule 40a, 18 cc. will be ejected on the down stroke, while if the lever is pressed to the left to use schedule 40, the five unit member 90 cc. will be ejected.

In operation, the parts 39, 40 and 41 having been 40 adjusted to permit an up stroke of a predetermined extent, the piston being in the full down position, liquid fumigant is permitted to flow through the inlet valve 6 and strainer 6a until a desired level has been reached within the device 45 which will at least be to the level of the inlet 8. This will fill the interior of the piston with liquid. Upon the first portion of the up stroke of the piston rod 11, the valve 12 will unseat. Further upward movement of the piston rod will carry the 50 entire piston with it. From this movement the liquid within the piston spills under the valve 12 through the piston head 13 and into the pump barrel. Upon the first portion of the down stroke movement, the valve 12 will seat on the piston head and further downward movement will force the fumigant upwardly between the walls of the piston 7 and the pump barrel 3 through the pump 55 29 and out of the outlet 28 to the distributing nozzle or tube (not shown). This top discharge is 60 to eliminate air or gas pockets which cause dribble when expanding after being put under compression by the stroke. This is a very important feature.

The coil spring 21 being under tension, intimate 65 and forced contact is made between the skirt 20 of the washer and the piston 7, thus preventing any escape of fumigant back into the dome 5 during the down stroke of the piston. This makes for accuracy of dosage.

70 While the invention has been shown and described with particular reference to a specific embodiment, yet the invention is not to be limited thereto but is to be construed broadly and restricted only by the scope of the claims.

I claim:

1. A displacement pump for volatile liquids comprising a pump barrel, including upper and lower portions, an annular washer attached to said barrel between said upper and lower portions, an inlet located in said upper portion, a valved outlet located in the upper part of said lower portion, and a movable piston located in said barrel and comprising a valved head cooperating with a piston rod and a cylindrical skirt portion of substantially smaller diameter than the internal diameter of the barrel and of sufficient length to contact with said washer during the entire stroke of the piston. 5
- 10 2. A displacement pump for volatile liquids comprising a pump barrel including upper and lower portions, an annular washer attached to said barrel between said upper and lower portions, an inlet located in said upper portion, a valved outlet located in the upper part of said lower portion, a piston rod in said barrel having a piston mounted on the end thereof and capable of limited movement with respect thereto, said piston consisting of an apertured head cooperating 15 with the end of said piston rod to form a valve and a cylindrical skirt portion of substantially smaller diameter than the internal diameter of said barrel and of sufficient length to contact with said washer during the entire stroke of the piston. 20
- 25 3. A displacement pump for volatile liquids comprising a pump barrel including upper and lower portions, an annular washer attached to said barrel between said upper and lower portions, an inlet located in said upper portion, a valved outlet located in the upper part of said lower portion, a movable piston located in said barrel and comprising an apertured head, a skirt portion of substantially smaller diameter than the internal diameter of said barrel and of sufficient length to contact with said washer during the entire stroke of the piston. 25
- 30 4. A displacement pump for volatile liquids comprising a pump barrel including upper and lower portions, an annular washer attached to said barrel between said upper and lower portions, an inlet located in said upper portion, a valved outlet located in the upper part of said lower portion, a movable piston located in said barrel and comprising a valved head and a cylindrical skirt portion of substantially smaller diameter than the internal diameter of the barrel and of sufficient length to contact with said washer during the entire stroke of the piston. 30
- 35 5. A displacement pump for volatile liquids comprising a pump barrel including upper and lower portions, an annular washer attached to said barrel between said upper and lower portions and comprising a flexible skirt portion and means 20 for urging said skirt portion inwardly, an inlet located in said upper portion, a valved outlet located in the upper part of said lower portion, and a movable piston located in said barrel and comprising a valved head and a cylindrical skirt portion of substantially smaller diameter than the internal diameter of the barrel and of sufficient length to contact with said washer during the entire stroke of the piston. 25
- 40 6. A displacement pump for volatile liquids comprising an outer casing, a pump barrel within said casing, an annular groove in the wall of said pump barrel, an outlet connected with said groove, an annular washer having a flexible skirt portion overhanging said groove and dividing said 35 pump barrel into upper and lower portions, a coil spring in said annular groove and encircling the washer skirt, an inlet in the upper portion of said pump barrel, a piston rod in said barrel having a piston mounted on the end thereof and 40 capable of limited relative movement with respect thereto, said piston comprising an apertured head cooperating with the end of said piston rod to form a valve and a cylindrical skirt portion of substantially smaller diameter than the internal 45 diameter of said barrel and of sufficient length to contact with said washer during the entire stroke of the piston.

WALLACE D. MERRILL.
